CLAIM

The ornamental design for a case for artificial lash extensions, as shown and described.

DESCRIPTION

FIG. 1 is a front left perspective view of a case for artificial lash extensions in accordance with the present invention.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is an exploded front left perspective view of the case for artificial lash extensions shown in FIG. 1.

The broken lines shown in the figures depict portions of the case for artificial lash extensions which form no part of the claimed design.
